US00D362511S

United States Patent [19]

Anderson et al.

[11] **Patent Number:** Des. 362,511[45] **Date of Patent:** ** Sep. 19, 1995[54] **CAP BLOCK**

[75] Inventors: **Peter L. Anderson**, Centreville; **Michael J. Cowell**, Leesburg; **Dan J. Hotek**, Chantilly, all of Va.

[73] Assignee: **Societ Civile des Brevets Henri C. Vidal**, Le Pecq, France

[*] Notice: The portion of the term of this patent subsequent to May 17, 2008 has been disclaimed.

[**] Term: **14 Years**

[21] Appl. No.: **11,818**

[22] Filed: **Aug. 16, 1993**

[52] U.S. Cl. **D25/113**

[58] Field of Search **D25/114-118; 52/596, 608; 405/284, 285**

[56] **References Cited**

[57] **CLAIM**

The ornamental design for a cap block, as shown and described.

DESCRIPTION

FIG. 1 is a perspective view of the cap block;
 FIG. 2 is a bottom plan view of the block of FIG. 1;
 FIG. 3 is a top plan view of the block of FIG. 1;
 FIG. 4 is a front elevational view of the block of FIG. 1;
 FIG. 5 is a back elevational view of the block of FIG. 1;
 FIG. 6 is a side elevational view of the block of FIG. 1;
 FIG. 7 is a sectional view taken along the line 7—7 in FIG. 2; and,
 FIG. 8 is a sectional view taken along the line 8—8 in FIG. 2.
